Specification for Design.

Patented Dec. 6, 1910.

Application filed July 19, 1910. Serial No. 572,749. Term of patent 7 years.

To all whom it may concern:

Be it known that I, SAMUEL S. SAMPLINER, a citizen of the United States, residing at Cleveland, in the county of Cuyahoga and State of Ohio, have invented a new, original, and ornamental Design for a Neckscarf or Muffler, of which the following is a specification, reference being had to the accompanying drawing, forming a part thereof.

The figure is a plan view of a neck scarf or muffler, showing my new design.

The design for a knitted neck scarf or

muffler herein shown comprises two connected end portions having substantially plain or straight bordered edges and central zig-zag portions intermediate of the said edges.

I claim:

The ornamental design for a neck scarf or muffler, as shown and described.

SAMUEL S. SAMPLINER.
